UNITED STATES PATENT OFFICE

113,898

DESIGN FOR A VENETIAN BLIND CORD LOCK OR SIMILAR ARTICLE

Jules Nisenson, New York, N. Y., assignor to Unit
Venetian Blind Supply Co., New York, N. Y.,
a corporation of New York

Application December 21, 1938, Serial No. 81,933

Term of patent 3½ years

To all whom it may concern:

Be it known that I, Jules Nisenson, a citizen of the United States of America and resident of New York city, county of New York, and State of New York, have invented a new, original, and ornamental Design for a Venetian Blind Cord Lock or Similar Article, of which the following is a specification, reference being had to the accompanying drawing, forming part thereof:

Figure 1 is a front view of a Venetian blind cord lock showing my new design.

Figure 2 is a side elevational view of Figure 1, as seen from the right side thereof.

Figure 3 is a rear elevational view as seen from the rear of Figure 1.

Figure 4 is a bottom plan view.

Figure 5 is a side elevational view as seen from the left side of Figure 1.

Figure 6 is a view taken similarly to Figure 2 with the tilt bar pin engaging lever in an altered position.

Figure 7 is a perspective view.

I claim:

The ornamental design for a Venetian blind cord lock or similar article, as shown and described.

JULES NISENSON.
